[57] CLAIM

The ornamental design for a toilet paper holder, as shown and described.

DESCRIPTION

FIG. 1 is a top, front and left side perspective view of a toilet paper holder showing my new design, the broken line depiction of the paper roll being for illustrative purposes only and forming no part of the claimed design;

FIG. 2 is a front elevational view thereof, the rear being plain and unornamented;

FIG. 3 is a top plan view thereof, the bottom being a mirror image of that shown;

FIG. 4 is a left side elevational view thereof, the right side being a mirror image of that shown; and

FIG. 5 is a vertical cross-sectional view thereof, taken along line 5—5 of FIG. 2.
